UNITED STATES PATENT OFFICE.

EUGENE F. SHAROFF, OF WASHINGTON, DISTRICT OF COLUMBIA.

SHOE-HOLDING DEVICE.

1,373,771.

Specification of Letters Patent.

Patented Apr. 5, 1921.

Application filed March 27, 1920. Serial No. 369,360.

To all whom it may concern:

Be it known that I, EUGENE F. SHAROFF, citizen of the United States, residing at Washington, in the District of Columbia, have invented certain new and useful Improvements in Shoe-Holding Devices, of which the following is a specification.

My invention relates to foot supports for shoe holding stands, the purpose being 10 broadly, to provide a simple device for holding a shoe on a standard while being shined.

The principal object of my invention is to provide such a device that may be applied to any form of standard, being readily attached and detached therefrom.

Another object is to provide such a device, in which shoe holding clamps are adapted to be actuated by mechanism having no direct connection to the clamps.

20 A further object is to provide a novel shoe holding clamp and adjustable actuating mechanism therefor, constructed with a minimum of parts and which may be cheaply made, readily assembled; being in 25 no way dependent upon any particular form of standard, nor requiring any alteration to be made therein.

A practical embodiment of my invention is illustrated in the accompanying drawings, 30 of which:

Figure 1, is a side elevation of a standard with my device applied thereto,

Fig. 2, is a front elevation showing the method of actuating the clamping arms,

35 Fig. 3, a plan view showing the location of the parts, and

Fig. 4, a transverse section on the line 4—4 of Fig. 1.

With the foregoing and such other objects 40 in view as will be apparent to those skilled in the art, and such as may be relative to devices of the character of my invention, my improved device, briefly described, comprises a plate adapted to be detachably disposed on a shoe standard, and having pivotally mounted thereon clamping arms adapted to engage over a shoe sole at their upper ends, and a ratchet lever pivoted to the plate and provided with a wedge member 45 adapted to engage between the lower ends of the clamping arms as the lever is raised, thereby bringing the upper ends of the arms together to clamp a shoe on the standard.

50 Reference being had to the accompanying drawings in which like reference characters

designate like parts throughout the several views and the specification, the invention, in detail, comprises a substantially U-shaped plate member 1, stamped or otherwise formed of metal, to be disposed over the body of a shoe standard 2 and secured thereto by fastening means 3, which in the preferred form of the invention comprise a pair or more of set screws.

65

Projecting forwardly of the plate 1 is a bracket 4 suitably secured thereto and provided at its outer end with a bearing 5 adapted to receive thereover a pair of clamping arms 6. The bearing 5 forms a 70 fulcrum on which the arms 6 are pivoted. These arms are retained on the bearing by suitable means, comprising, in the present instance, a cotter pin 7.

Below the bearing 5, the lower portions of 75 the arms 6 extend in substantially parallel planes and are provided with flared ends 8. The upper ends of the arms are flared in a similar manner and are extended divergently to slightly above the top of the 80 standard and at either side thereof, the terminal portions being bent inwardly to form clamps 9 adapted to be engaged over the sole of a shoe when placed on the standard.

85

The clamp actuating mechanism comprises a lever 10 suitably pivoted at one end to the plate 1 and disposed adjacent the lower end therof. Directly beneath the lower ends 8 of the clamping arms, a wedge 90 member 11 is suitably mounted on the lever 10. This wedge is substantially arcuate in elevation and the entering edge thereof is normally engaged slightly between the flared ends 8 as clearly shown in Fig. 2. 95 Suitable latch mechanism generally designated as at 12, is carried by the lever to engage the toothed sector 13 mounted on the plate 1, whereby the lever may be adjusted to be held at points desired.

100

When a shoe is placed upon the standard and it is desired to secure the same thereon, the lever 10 is drawn upwardly by the attendant, whereupon the wedge 11 will force apart the lower ends 8 of the arms 6 causing the upper ends to be forced together and clamp over the shoe sole. By the provision of the latch mechanism on the lever, the clamp may be locked at the desired point, allowing of accommodation for different degrees of tightness and various widths of shoes.

105

110

I lay particular stress upon this wedge actuating means for the clamp, as with this construction there is no direct connection of parts between the actuating means and the 5 clamping means. This is a radical departure from the link and lever construction of the devices in the art. Furthermore the entire assembly is designed to be applied, by means of its mounting on the plate 1, to any 10 standard foot rest merely by attaching the plate thereto by means of the set screws.

While I have shown and described certain materials and specific details entering into the construction of my invention, I 15 desire it to be understood that I do not limit myself to them, but that any such may be used and such changes made, as will fall within the scope of the invention as claimed.

I claim:

- 20 1. A shoe holding device comprising a member adapted to be disposed on a shoe standard, shoe clamping means on said member and actuating mechanism for said means, independently disposed on the member.
2. A shoe holding device comprising a shoe standard, clamping arms pivotally mounted thereon and adjustable wedge mechanism on said standard adapted to be 30 engaged therebetween for actuating said arms.
3. A shoe holding device comprising a member adapted to be attached to a shoe standard, clamping arms pivoted thereon, a wedge member adapted to be engaged between said arms for clamping actuation thereof on movement of said wedge member, and means on said first named member for adjusting said wedge member.
- 40 4. A shoe holding device comprising a

member adapted to be attached on a shoe standard, arms pivoted thereon, clamps at one end of said arms, a wedge engaged between the opposite ends of the arms and adjustable means carried by the member 45 for entering said wedge between said arms whereby to actuate the clamps on said arms.

5. A shoe holding device comprising a plate detachably mounted on a shoe standard, a bracket extending therefrom, arms 50 pivoted on the bracket, clamps at one end of said arms, a lever pivoted on said plate and extending beneath said arms at the other end, a wedge on the lever to enter between said arms on manipulation of the 55 lever and means to adjust said lever to lock said clamps.

6. A shoe holding device comprising a member detachably mounted on a shoe standard, a bracket extending therefrom, 60 arms pivoted on the bracket, clamps formed at one end of said arms, flared portions at the other end of said arms, a lever pivoted on said member and extended beneath said bracket and arms, an upstanding wedge on 65 said lever to engage between the flared portions of said arms, and means to adjust said lever to lock the clamps.

7. A shoe holding device comprising a standard, a bracket extending therefrom, 70 arms pivoted on said bracket, said arms having their upper ends bent to form clamps and being provided with flared lower ends, a wedge member on the standard to engage between the flared ends of 75 said arms for operation of the clamps, and means for adjustably locking said wedge and clamps.

In testimony whereof I affix my signature.
EUGENE F. SHARKOFF.
